UNITED STATES PATENT OFFICE.

WILLIAM H. BROWN, OF WINCHENDON, MASSACHUSETTS, ASSIGNOR TO THE BROWN PACKAGE COMPANY, OF WINCHENDON, MASSACHUSETTS, A CORPORATION OF MASSACHUSETTS.

STAVE MACHINE.

Application filed July 3, 1922. Serial No. 572,464.

This invention relates to stave forming machines and the like and particularly to a machine for giving to such an article as a stave blank the desired edge angle and longitudinal taper, while at the same time forming a tongue and groove on its opposite edges.

In machines of this sort the several factors involved make it difficult to provide for accurate adjustment for any considerable difference in size either as to length or as to the diameter of the package to be produced. It has furthermore been found difficult in machines involving more than one of these operations to get a proper feed of the work and a proper speed of operation.

In accordance with my present invention I am able to combine the above mentioned operations with a maximum degree of adjustment and of speed and at the same time handle the work in a manner most convenient for subsequent operations.

As illustrative of my invention, I have shown in the accompanying drawings an embodiment which involves convenient construction of parts and satisfactory combinations of elements, although it will be understood that the machine may be variously modified in structure, combination and design. Throughout the specification and drawings like reference characters are employed to indicate corresponding parts and in the drawings:

Fig. 1 is a side elevation of the machine in accordance with my invention.

Fig. 2 is a plan view thereof.

Fig. 3 is a section on the line 3—3 of Fig. 2 and

Figs. 4 and 5 are diagrammatic illustrations of the slide movement.

In the embodiment of my invention shown in the drawings I provide a suitable bed 1 mounted at a convenient level on legs 2 and provided at one end with an adjustable hopper 3 for supporting a column of stave blanks which are to be beveled, tapered and matched by the machine. The bed 1 is provided with a longitudinal slideway 4 in which is mounted a reciprocating work slide which preferably is formed as an open rectangular frame comprising side rails 5 and cross bars 6. Anchored to the cross bars 6 and extending beneath and beyond the hopper 3 is a narrow central longitudinal work support 5' on which is a feed dog 5" for

engaging the end of the stave and feeding it to the cutters. Depending from the bed 1 is a pair of spaced brackets 7' within which are journaled oppositely disposed studs 7. Pivoted on studs 7 below the slideway is a pair of transversely disposed spindle heads 8. These heads 8 are mounted to be adjusted about the studs 7 and be held each by a nut 9 threaded on a fixed bolt 10 in any desired angle of position. The bolts 10 are set through the brackets 7' and the heads 8 are provided with elongated slots 10' (Fig. 3) to receive said bolts, these slots permitting a limited arcual adjustment of the heads relative to the brackets. Each head 8 is provided between its ends with an angularly disposed slideway 11 within which reciprocate spindle slides 12, the slides 12 having spindle bearings 13 in which are mounted cutter spindles 14. In the lower offset side of each slide 12 is mounted a motor 15 whose armature shaft 15' is aligned with and connected to the cutter spindle 14 so as to provide a direct and independent drive for each cutter.

On the lower face of the bed 1 and on each side of the slideway 4 is a transverse slideway 16 in which is mounted a slide 17 carrying on its upper face a roller stud 18 which projects up through the opening of the work slide frame 5 and into the slot 19' of a templet or guide 19. There is one of these templets 19 on each side of the work slide and these extend longitudinally of the slide frame and across its opening, being adjustably connected at each end to the end cross pieces of the side frame so that the angularity of the slot 19' may be adjusted with reference to the line of travel of the work in passing the cutters. The cutters 20 are mounted on the upper ends of the spindles 14, they being of the usual rotary type of matching cutters, one forming the tongue and the other the groove on opposite sides of the stave. Each stud carrying slide 17 is connected to the spindle carrying slide 12 by a link 21, so that as the work slide carrying the guide or templet 19 is advanced longitudinally, the slide 17 is moved transversely of the machine under the influence of the angularly disposed slot 19' and through the medium of the link 21 moves the spindle slide 12 also transversely of the machine and thus presenting its cutter accurately and uniformly to the edge of the slab or stave blank B.

The slab is held on the central work support 5' during the cutting operation by a presser bar 22 yieldingly forced down by springs 23, the bar being carried in a pair of yokes 24 which span the slideway of the machine. The accurate advance of the cutters in the true plane to which they are swung and adjusted and which is at right angles to the radius of curvature of the stave and accurately centered on the edge of the stave, is very important. It will be seen that if the cutter spindle should rock during its advance to form a taper, the tongue or groove would depart from the center of the stave edge and in case of a stave of any length would run off. By arranging the spindle slides 12 at an angle to the horizontal slides 17, which latter slides are operated from the templet 19 and are operatively connected with the angularly disposed spindle slides 12, a motion is imparted to the cutter spindles which is the resultant of a horizontal and a vertical tendency so that the centers of the cutters are maintained against the edges of the stave approximately centrally of the depth of the stave throughout the entire travel of the stave past the cutters.

The pieces which form the stave hopper 30 are angular members disposed to engage the corners of the blanks or stave slabs S, the two outer pieces being adjustable relative to the two inner pieces as indicated at 3', to accommodate staves of different length. The staves S feed automatically by gravity, the lower stave being supported by the elongated end of the support 5'. When the dog 5² engages the rear end of the stave the slide begins to return, pulling out the bottom stave and advancing it towards the cutter.

The reciprocation of the work slide 5 is by a drive at the base of the machine. A transverse power shaft is provided at 25 on which is a small gear 25' meshing with a large gear 26 and driving a cam faced gear 27 meshing with a corresponding gear 28 which rocks a vertical lever 29 by a link 29'. The upper end of the vertical lever is slotted as at 29^a and one end of a link 35 is adjustably pivoted within the slot 29^a. The link 35 is connected at its opposite end to the lower side of the work slide 5 and by the proper proportioning of the gears, the slide is given a fast motion in its travel between the stave hopper and the cutters and a slow motion past the cutters.

The finished staves are withdrawn from the work support 5' by a pointed dog 30 positioned at the extreme feed movement of the slide 5 and having a curved beak by which it is adapted to ride over the end of the stave and against the tendency of gravity. A weight 31 is provided on the dog 30 sufficient to cause its sharpened point 30' to

catch in the face of the stave and hold it against the return motion of the slide.

In adjusting the machine, the diameter of the package or pail and the corresponding width of the stave to be used is determined. The stave blanks are then sawed with the required curvature from the blank slabs of the required thickness. These slabs are fed into the pieces 3 which form the stave hopper, adjustment being made for the length of the stave. The spindle heads 8 are then swung on their pivots 7 and clamped firmly to give to the cutter spindles proper radial angle at the edge of the stave and the lateral guides are adjusted to give the desired taper. The end of the link 35 is set in the slot 29^a of the lever 29 so as to give the required length of throw to the slide and the machine is ready for operation. The motor 15 of the cutter spindles 14 is turned on and the power shaft 25 started. The slide 5 is advanced and the cutters taper, bevel and joint the edges with absolute accuracy and uniformity.

Various modifications in the details of structure and arrangement of the parts, as well as the substitution of equivalent devices and movements, may all be made each without departing from the spirit of my invention if within the limits of the appended claims.

What I therefore claim and desire to secure by Letters Patent is:

1. In a machine for tongue and grooving and tapering pail staves, a frame having a longitudinal slideway, a work slide movable in said slideway, a pair of transversely disposed spindle heads, means for angularly adjusting said spindle heads, each of said heads having a slideway disposed transversely of the machine, a spindle slide in each of said slideways and having a suitable spindle bearing, a cutter spindle in said bearing of each slide, cutters mounted on the upper ends of said spindles and positionable adjacent the line of travel of the work slide, templets adjustably supported at each end and disposed longitudinally of the machine on each side of the main slide, a transverse slide on each side of the machine mounted on suitable slideways, templet engaging members on each of said transverse slides, and a connection between the last mentioned transverse slides and the spindle slides.

2. In a machine for tongue and grooving and tapering pail staves, a frame having a longitudinal slideway, an open slide movable in said slideway and having a central longitudinally disposed stave support, a stave hopper disposed at one end of said slideway, a feed device on the slideway and disposed to engage and draw the bottom stave from the hopper, a pair of transversely disposed spindle heads pivoted to

the frame below the slideway, means for adjustably holding said heads in angular adjustment on their pivots, each of said heads having a slideway disposed transversely of the machine, a spindle slide in each of said slideways, and having a suitable spindle bearing, a cutter spindle in each bearing, cutters mounted on the upper ends of said spindles and positionable adjacent the line of travel of the stave support of the slide, slotted templets adjustably supported at each end and disposed longitudinally of the machine on each side of the main slide and across the open slide, a transverse slide on each side of the machine mounted on suitable slideways, said transverse slide having engaging members projecting within the slots of the templets, and a link connecting the last mentioned transverse slides with the spindle slides.

3. In a machine for tongue and grooving and tapering pail staves, a stave blank guideway, means for advancing a stave blank therealong, a templet, a pair of rotary tongue and groove stave-tapering cutters pivotally mounted at opposite sides of said guideway, and means operated from said templet for imparting to said cutters

a motion which is the resultant of a horizontal and a vertical tendency effective to constantly maintain the centers of the cutters against the edges of the stave blank approximately centrally midway between the faces of said blank throughout the entire travel of the blank past said cutters. 35

4. In a machine for tongue and grooving and tapering pail staves, a stave blank guideway, means for advancing a stave blank therealong, a templet, a pair of rotary tongue and groove stave-tapering cutters 40 pivotally mounted at opposite sides of said guideway, angularly disposed slides carrying said cutters, and horizontally disposed slides operated from said templet and operatively connected with said angularly disposed slides for imparting to said cutters a motion which is the resultant of a horizontal and a vertical tendency effective to constantly maintain the centers of the cutters against the edges of the stave blank 45 and at points disposed approximately midway between the faces of said blank throughout the entire travel of the blank past said cutters. 50

In testimony whereof I affix my signature.
WILLIAM H. BROWN.
